DESIGN FOR A NOVELTY POSTCARD BOX

Max Fisch, Brooklyn, N. Y.

Application May 19, 1941, Serial No. 101,012

Term of patent 3½ years

To all whom it may concern:

Be it known that I, Max Fisch, a citizen of the United States and resident of Brooklyn, New York, in the county of Kings and State of New York, have invented a new, original, and ornamental Design for a Novelty Postcard Box, of which the following is a specification, reference being had to the accompanying drawing, forming a part thereof.

Fig. 1 is a perspective front view of a novelty postcard box, showing my new design.

Fig. 2 is a side elevational view of the same.

Fig. 3 is a perspective rear view of the same showing the cover partially closed.

Fig. 4 is a bottom plan view of the same.

I claim:

The ornamental design for a novelty postcard box, as shown.

MAX FISCH.
